UNITED STATES PATENT OFFICE.

ALBERT L. FLEGEL, OF RACINE, WISCONSIN.

MAGAZINE-PEN.

1,304,292.

Specification of Letters Patent. Patented May 20, 1919.

Application filed January 20, 1919. Serial No. 272,093.

To all whom it may concern:

Be it known that I, ALBERT L. FLEGEL, a citizen of the United States, and resident of Racine, in the county of Racine and State 5 of Wisconsin, have invented certain new and useful Improvements in Magazine-Pens; and I do hereby declare that the following is a full, clear, and exact description thereof.

10 My invention relates to new and useful improvements in pens of that type adapted to hold a body of material adjacent the pen point, which is soluble to impart color to liquid which adheres to the pen point and associated parts upon dipping said parts 15 into any suitable liquid, thus transforming the liquid held by the pen into a suitable writing medium and affording an exceedingly convenient arrangement for writing 20 under conditions where ink is not readily available, in addition to procuring a material economy, since the writing fluid is only made as it is used, thus avoiding the deterioration and evaporation incidental to the 25 provision of permanent writing fluids.

It is in general my object to simplify and otherwise improve the structure and to increase the efficiency of pens of this character.

More particularly, it is my object to provide 30 for a magazine feed of the soluble ink material, to insure an adequate supply thereof adjacent the pen point for an indefinitely long period, a further object in this connection residing in the provision of an arrangement 35 for insuring a positive feed of the ink material as it is used up by dissolving in the writing liquid.

A further object resides in the provision 40 of an arrangement for holding the soluble ink material in proper relation to the pen point or nib, which serves at the same time to retain a maximum amount of liquid on the nib and in proximity to the ink material whereby to form a reservoir for such liquid, 45 permitting a maximum amount of writing with a single immersion of the pen in water or whatever convenient liquid is used.

With the above and other objects and advantages in view, which will be apparent as 50 the description proceeds, my invention resides in the novel features of construction, combination and arrangement of parts as hereinafter more particularly described and defined by the appended claims.

In the accompanying drawings: 55
Figure 1 is a longitudinal sectional view through a pen embodying my invention.

Fig. 2 is an elevational view of the lower portion of the pen, looking toward one side thereof.

Fig. 3 is a similar view looking toward the opposite side of the pen.

Fig. 4 is a transverse sectional view through the pen on the line 4-4 of Fig. 1.

Referring now more particularly to the 65 accompanying drawings, the present embodiment of my invention includes a tubular head section 10, formed of compressed fiber or other suitable material and having an internal diameter at one end portion corresponding to the transverse curvature of an ordinary pen point or nib 11 whereby to frictionally receive and retain said nib, it being particularly noted that a free passageway is thus afforded through the head member 70 of the pen communicating with the channel formed by the concavity of the pen point or nib. A metallic casing 12 has one end portion shrunk on the head portion 10 and is provided with an intermediate annular 75 ledge 13 on its outer periphery forming a stop for the handle tube 14 engaging over the other end portion of the casing, said handle tube telescopically receiving the inner end of the head portion 10 and having 80 its remote end portion turned inwardly to form an end closure 15 for the tube.

To hold the soluble ink material adjacent the pen, I provide a retainer member which constitutes, in the present instance, a clip 85 plate 16 having lateral wing extensions 17 at one end adapted to embrace the side edge portions of the pen point and frictionally engage therewith to hold the clip plate in place. The other end of the clip plate is 90 bent inwardly at 18 to substantially close the channel of the pen point preferably immediately inwardly of the usual spreader aperture of the pen point. Thus the pen point and the clip may be individually or both 95 readily removed and replaced. The ink material may be supplied in the form of pellets, but it is preferably provided in the form of an elongated stick 20 as shown in Fig. 1. When pellets are used, said pellets 100 are balls are of such diameter as to pass freely between the clip body 16 and the pen point and are adapted to be stored in the

tubular head member 10 and in the handle 14 of the pen, it being noted that the inner end of the clip body 16 forms a stop preventing loss of balls or pellets from the interior of the pen by its disposition adjacent the side of the tubular member 11 remote from the pen point. When the stick 20 is used, it extends a considerable distance into the handle and a metallic weight 21 is fixed 10 on the inner end of the stick to more positively insure the gravity feed of the ink material to proper position with respect to the pen point, as said material is gradually used up by solution in the writing liquid, it being 15 appreciated that by the nature of the stick, the same will last for a great length of time.

While I have shown my invention as associated with a particular form of holder 30 for the pen point, it will be appreciated that 20 my invention may also be associated with any pen point holder which embodies a longitudinal passageway adapted to communicate with the channel of the pen point and to afford a magazine chamber for the soluble 25 ink material. It will further be appreciated that any suitable mounting may be afforded for the retainer and reservoir forming member for the soluble ink material, constituting the clip in the present instance.

30 What is claimed is:

1. A pen of the class described comprising a tubular non-metallic body member, a ferrule sleeve having its lower portion disposed about the body member and having its upper portion offset therefrom, a handle member detachably engageable with said offset portion, a transversely curved pen point having its width substantially equal to the internal diameter of the body member 40 whereby to frictionally engage within said

body member and be thus held in place, a clip comprising a plate having wings at its side portions bent to embrace and frictionally engage the sides of the pen point and having its outer end portion bent to close 45 the channel of the pen point, said clip plate forming one side of an ink chamber having its other side formed by said pen point, and a magazine supply of soluble ink material in the passageway of the pen body adapted 50 for feeding movement into the said chamber, the inner end of the clip plate being in juxtaposition to the end of the body member to form a closure for the interior thereof preventing movement of ink material from the 55 body member exterior of the chamber.

2. A pen of the class described including a tubular body member, a transversely curved pen point carried by said body member, the passageway of said body member communicating with the channel formed by the concavity of the pen point, a closure member extending between the side edges of the pen point outwardly of the body member and having a portion bent to close the channel 60 of the pen point adjacent the nib, said closure member forming one side of a chamber having its other side formed by the pen point, an elongated stick of ink material loosely disposed in the passageway of the 65 body member, with its end seating in the said chamber of the pen point, and a weight secured on the upper end of the stick of ink material to procure positive feeding movement thereof to the pen point as said material is dissolved.

In testimony that I claim the foregoing I have hereunto set my hand at Racine, in the county of Racine and State of Wisconsin.

ALBERT J. FLEGEL.
